US0D1021412S

(12) **United States Design Patent** (10) **Patent No.:** **US D1,021,412 S**
(45) **Date of Patent:** **** Apr. 9, 2024**

(54) **STORAGE BOX**

(71) Applicant: **NINGBO BOTONG PLASTIC CO., LTD**, Ningbo (CN)

(72) Inventor: **Zengyao Tong**, Ningbo (CN)

(73) Assignee: **NINGBO BOTONG PLASTIC CO., LTD**, Ningbo (CN)

(**) Term: **15 Years**

(21) Appl. No.: **29/827,044**

(22) Filed: **Feb. 17, 2022**

(30) **Foreign Application Priority Data**

Sep. 29, 2021 (CN) 202130647207.9
